FUSE

Marvin L. Mathsen, Rockaway, N. J.

Application January 11, 1935, Serial No. 1,322

7 Claims. (Cl. 102—37)

(Granted under the act of March 3, 1883, as
amended April 30, 1928; 370 O. G. 757)

The invention described herein may be manufactured and used by or for the Government for governmental purposes, without the payment to me of any royalty thereon.

5 The subject of this invention is a fuse.

The purpose of the invention is to provide a compact, safe and reliable mechanical time fuse which is also capable of functioning on impact and in which the parts are formed and assembled

10 with a view towards manufacturing expediency.

The invention is characterized by a clock-work mechanism which carries a firing pin and is movable longitudinally of the fuse and by a novel arrangement for controlling the clock-work mechanism.

To these and other ends, the invention consists in the construction, arrangement and combination of elements described hereinafter and pointed out in the claims forming a part of this specification.

A practical embodiment of the invention is illustrated in the accompanying drawings, wherein:

Fig. 1 is a longitudinal sectional view of the fuse with the parts in the safe position.

Fig. 2 is a view in side elevation with parts in section.

Figs. 3 and 4 are sectional views on the corresponding lines of Fig. 1.

30 Fig. 5 is a longitudinal sectional view of the fuse in the armed position.

Fig. 6 is a sectional view on the line 6—6 of Fig. 5.

35 Fig. 7 is a longitudinal sectional view of the fuse when in firing position due to functioning of the timing unit.

Fig. 8 is a sectional view on the line 8—8 of Fig. 7.

40 Fig. 9 is a longitudinal sectional view of the fuse when fired on impact.

Fig. 10 is a sectional view on the line 10—10 of Fig. 9.

Fig. 11 is a detail sectional view showing the arming bolt.

45 Referring to the drawings by characters of reference, the fuse comprises a chambered body 5 whose front end is closed by a head 6 having a tubular portion 7 disposed within the body and a flange 8 extending over the rim of the body. The head is slidably mounted with respect to the body, its inward movement being opposed by a ring 9 secured to the body by shear pins 10 (Fig. 2) and its outward movement being restrained by pins 11

threaded in the body and normally disposed at the inner end of blind slots 12 in the tubular portion 7.

A plurality of groups of blocks 13 each group carried by a spring 14, are interposed between the flange 8 of the head and the rim of the body and when in place prevent inward movement of the blocks are confined against the tendency of their springs to throw them from the fuse by means of a cap 15 fitting over the outer end of the head.

The cap is part of a vane assembly which is removed from the fuse during flight and is carried by a shaft 16, being retained between a collar 17 and a propeller or vane 18. The cap is held against rotation by a pin 19 extending into the head 6. The inner portion of the shaft threadedly engages a nut 20 which is housed in a recess in the head 6 and has spaced flanges 21 and 22 whereby it is rotatably supported by a plate 23 secured to the head by screws 24.

A gear wheel 25 secured to the shaft 16 and a gear wheel 26 secured to the nut 20 and having one more tooth than the gear 25 are both in mesh with a pinion 27 mounted on a shaft 28 carried by the plate 23.

20 A timing unit 29 which is a conventional clock-work mechanism is slidably and rotatably mounted in the chambered body 5 and carries a firing pin 30 which projects through an aperture 31 in the rear end of the body. The firing pin also extends into an aperture 32 in a base 33 which rotatably carries the body by a two-part retaining ring 34. The firing pin is slidable in the aperture 32 but is non-rotatably associated with the walls of the aperture by a non-circular shape. A 35 spring 35 confined between the base and a collar 36 on the firing pin urges the firing pin rearwardly.

The firing pin is normally restrained against the action of the spring by a conventional arming bolt 37 (Fig. 11) which is mounted in a passage 38 in the body and has a bifurcated inner end 39 straddling a round part 40 of the firing pin. The bolt is ejected from the fuse by a spring 41 when the usual arming wire 42 is withdrawn during 45 launching of the bomb as is well understood in the art.

On the front or outer end of the timing unit 29 there is a guide pin 43 inserted in a recess 44 in the head. On the same end, a disc 45 (Fig. 3) 50 having a peripheral recess 46 is adapted to be rotated when the timing unit is in operation. The disc carries a flat spring 47 having a finger 48 (Figs. 1, 3, and 9) which extends through an aperture 49 in the disc and bears against a lug 50 55

on the timing unit when the timing unit is held by the arming bolt in its foremost position with the spring pressed against the head 6. In this position of the parts the disc is held against rotation 5 and it is only free to rotate when the timing unit has been displaced and the spring, being thereby released, disengages its finger from the lug 50.

The ring 9 is formed with a slot 51 for receiving a timing lever 52 and a stop lever 53 respectively 10 mounted on pivot pins 54 and 55 carried by the ring. The timing lever is disposed longitudinally of the fuse on the outside of the timing unit and its front arm is normally urged towards the axis of the fuse by a spring 56. A pin 57 carried by 15 the cap 15 and removable therewith extends through an aperture 58 in the head 6 and opposes movement of the lever under the action of the spring 56. The front arm of the lever is formed with a lug 59 engaging the periphery of the disc 20 45. The lever is thereby held against the action of the spring 56 until the recess 46 in the disc is brought into line with the lug. One corner of the lug 59 also engages the front edge of the timing unit when the latter is in the safe position shown 25 in Fig. 1.

When the timing lever is thus held against the action of the spring 56 its rear arm is maintained in engagement with the stop lever 53 and holds the stop lever in a position radially of the 30 fuse with one arm interposed in the path of movement of the timing unit. The stop lever holds the timing unit against the action of the spring 35 after the arming bolt 37 has been ejected.

The base 33 carries a number of plungers 35 Figs. 1 and 4 for frictionally engaging the rear end of the body 5. The base also carries a pin 61 which rides in a slot 62 in the body and by engaging the ends of the slot prevents setting of the timing unit between zero and 8 seconds. The 40 usual time scale 63 is inscribed on the body and is read by a reference mark 64 on the base. The body and base are docked against relative rotational movement, after the timing unit is set, by means of a set screw 65, which in turn is held by a flat spring 66.

The fuse is in the safe or unarmed position when the parts are arranged as shown in Fig. 1 with the arming bolt 37 in place and with the stop lever 53 in rear of the timing unit. The timing unit is 50 set according to the indication on the scale 63 by rotating the body 5 relative to the base 33 which is attached to the bomb 67. This has the effect of angularly displacing the timing lever 52 while the timing unit including the disc 45 with recess 55 46 is held stationary by virtue of the non-circular engagement of the firing pin in the base.

When the bomb is launched, the arming wire 42 is withdrawn, the arming bolt 37 is ejected, the timing unit is moved by the spring 35 until arrested by the stop lever 53, which movement is sufficient to enable the spring 47 to release the disc, and the vane 18 commences to rotate. After an interval the vane has unthreaded itself from the nut and falls clear of the fuse carrying the cap 15. The removal of the cap frees the blocks 13 which are thrown out and also withdraws the pin 57 from engagement with the timing lever 52.

The disc 45 is being rotated by the timing unit 70 and after an interval designated by the scale 63, the recess 46 in the disc is brought into line with the lug 59 on the timing lever 52 and the latter is moved by its spring 56 to free the stop lever 53. The timing unit and firing pin are now moved 75 rearwardly to firing position by the spring 35 as

shown in Fig. 7, the stop lever being rotated to one side.

If impact occurs before the timing unit has functioned as just described, the head 6 is driven rearwardly and carries with it the ring 9 whose 5 shear pins 10 are severed. The timing and stop levers mounted in the ring are accordingly displaced and the head drives the timing unit and firing pin into the firing position as shown in Fig. 9.

I claim:

1. In a fuse, a base, a body rotatably mounted on the base, a head slidably mounted on the body, a ring releasably attached to the body and normally opposing inward movement of the head, a timing unit slidable within the ring, a firing pin carried by the timing unit and non-rotatably associated with the base, a spring for moving the firing pin to fired position, a removable bolt normally holding the firing pin against the action of the spring, a rotatable disc forming part of the timing unit and having a peripheral recess, a spring carried by the disc and engaging the timing unit to hold the disc against rotation, said spring held in engaging position by the head when the bolt is in place, a timing lever carried by the ring and riding on the periphery of the disc, and a stop lever carried by the ring and held by the timing lever in the path of movement of the timing unit.

2. In a fuse, a base, a body rotatably mounted on the base, a head mounted on the body, a timing unit slidable within the body, a firing pin carried by the timing unit and non-rotatably associated with the base, a spring for moving the firing pin to fired position, a removable bolt normally holding the firing pin against the action of the spring, a rotatable disc forming part of the timing unit and having a peripheral recess, a spring carried by the disc and engaging the timing unit to hold the disc against rotation, said spring held in engaging position by the head when the bolt is in place, a timing lever carried by the body and riding on the periphery of the disc, and a stop lever carried by the body and held by the timing lever in the path of movement of the timing unit.

3. In a fuse, a base, a body rotatable with respect to the base, a timing unit slidable within the body, a firing pin carried by the timing unit and non-rotatably associated with the base, a spring for moving the firing pin to fired position, a rotatable disc forming part of the timing unit and having a peripheral recess, a timing lever carried by the body and riding on the periphery of the disc, and a stop lever carried by the body and held by the timing lever in the path of movement of the timing unit.

4. In a fuse, a base, a body rotatable with respect to the base, a timing unit slidable within the body, a firing pin carried by the timing unit and non-rotatably associated with the base, a spring for moving the firing pin to fired position, a rotatable disc forming part of the timing unit and having a peripheral recess, and a timing lever riding on the periphery of the disc and controlling movement of the timing unit under the action of the spring.

5. In a fuse, a body, a head on the body, a timing unit mounted for longitudinal movement in the body, a spring for moving said unit, a starting control member for said unit and means removable during flight for normally holding the timing unit with the control member in inoperative position against the head, means for limit-

ing movement of the timing unit, and means under control of the timing unit for inoperating the limiting means.

6. In a fuse, a body, a head on the body, a timing unit mounted for longitudinal movement in the body, a spring for moving said unit, a starting control member for said unit and means removable during flight for normally holding the timing unit with the control member in inoperative position against the head.

7. In a fuse, a timing unit, a firing pin carried by said unit, a spring for moving the firing pin, time control means for normally holding the timing unit against the action of the spring, and means operable on impact for displacing the timing unit and time control means.

MARVIN L. MATHSEN.
